UNITED STATES PATENT OFFICE.

ARTHUR R. MASON AND OTTO C. FAILING, OF MEDFORD, OREGON, ASSIGNEES TO
ACCURATE GASOLINE RECORDING COMPANY, A CORPORATION OF OREGON.

RECORDING AND SALES-CHECK MECHANISM FOR FLUID-DISPENSING PUMPS.

Application filed August 17, 1927. Serial No. 213,688.

Our invention has for its object means whereby the customer and salesmen are each provided with a check or printed slip showing the amount of fluid dispensed at each 5 operation of a pump, and wherein a further slip or paper strip is wound on a spool within the mechanism retaining registered thereon a total of the fluid dispensed in all previous operations.

10 By our device the purchaser of fluid dispensed is provided with a slip on which is distinctly registered the actual fluid dispensed exclusively to him in any given transaction.

15 Moreover the salesman operating the pump is provided with a similar slip by which the fluid dispensed by him from any given pump is separately recorded, while the owner of the pump is provided with a record 20 of the total fluid dispensed and a record of each transaction.

A further object of our invention is mechanism adapted to be operated in combination with a fluid dispensing pump such as that 25 generally employed for dispensing gasoline or fuel oil at service stations and oil in measured quantities from containers.

Our mechanism is simple, efficient and readily accessible and does not further complicate any of the operations heretofore performed on conventional pumps.

By referring to the accompanying drawing our invention will be made clear.

In the drawing Fig. 1 is a side view partly 35 in section showing a conventional gasoline dispensing pump to which our invention has been applied.

Fig. 2 is a plan view of a portion of the operating mechanism with the dispensing 40 pump operating handle and piston rack and with certain of the parts left out to better illustrate the operation.

Fig. 3 is a side view of fragmentary portions of Fig. 2.

45 Fig. 4 is an enlarged detail illustrating the operation of the pawl and ratchet mechanism of Figs. 1 and 2.

Fig. 5 is a fragmentary section through a front portion of the casing of the mechanism 50 showing the manner in which the record slips are discharged.

Throughout the figures similar numerals refer to identical parts.

The cylinder of a conventional fluid dis-

placement pump is shown at 1 wherein is operated the piston 2, to withdraw gasoline or other fluid from the tank 3 and distribute the same from the nozzle 4, the gasoline being transferred from the tank 3 through the pipes 5 to the container 6 upon the operation of the rack 7 by the handle 8 all in the conventional manner.

55 Referring particularly to Fig. 2 the rack 7 is operated by the handle 8 which rotates the pinion 9 which in turn rotates the second pinion 10 actuating the recording mechanism gear 11.

This latter is carried freely on the shaft 12, the latter being supported in the boxes 13, 14.

60 Mounted on the gear 11 are a plurality of posts 15, 16 supporting a like plurality of pawls 17, 18 respectively.

65 These pawls are adapted to engage the skew ratchet wheel 19 which is integrally connected with the strip feeding drum 20, so that with a motion of the gear 11 in the direction of arrow 21, the pawls engage the ratchet and cause the drum 20 to rotate, advancing the paper strips 22, 23, 24 in synchronism with the movement of the piston 2 and therefore in direct proportion to the fluid dispensed by the pump.

70 The ratchet 19 and feeding wheel 20 are freely mounted upon the shaft 12 and are frictionally engaged therewith through the friction disc 25 splined to the shaft 12 at 26 and held against the wheel 20 by the helical spring 27, the ratchet bearing against the collar 28 carried on the shaft 12 on the other side.

75 Any conventional characters or printing or embossing may be provided on the paper strip or strips or they may be impressed as issued with suitable characters or embossing as follows.

80 The clutch plate 25 actuated by the spring 27 provides a driving friction against the drum 20 to enable the drum to be moved upon overcoming the said friction into any desired position with respect to the shaft and gear train and so as to secure a perfect registration of the paper strips when inserted, and moreover, to prevent tearing of the paper strips, should they, for any reason, stick during the operation of the machine.

85 At 37 is a printing or embossing wheel 90 geared to the drum 20 having raised graduations or punched strips 38, so that the several

strips of paper being delivered between the drum 20 and the wheel 37 may be punctured or embossed to indicate the proportional movement of the pump piston and therefore the fluid delivered from the pump.

5 The paper strips are supplied from any conventional source as reels, positioned elsewhere in the box, well-known but not shown, and the said strips 22, 23, 24, are passed between the drum 20 and wheel 37.

10 After passing between the wheels 20 and 37 the paper record advances through the carrier tube 39 and after the pumping operation is completed, is ready for delivery from the safety casing 40 hinged at 41.

15 This safety casing and the cutting knife combined therewith for severing the paper strips is made the subject of a separate and co-pending application by us, Serial No. 213,689 filed Aug. 17, 1927, to which reference 20 is herein made.

25 The paper strip 22 is a complete record of all of the pump transactions to date and the two additional slips 23 and 24 which are duplicates thereof are, one for the customer and one for the particular salesman who has handled the transaction.

30 A spring 29 likewise forces the gear 11 causing its hub 30 to ride against the fixed pin 31.

35 This pin has a wedge shaped end and normally during operation rides against the face 31 of the hub 30 and when the piston 2 is in the lowest possible or zero position, the end of the pin 31 engages within the slot 33 while as soon as the handle 8 is rotated, the first movement of the gear 11 causes the face 32 to advance, forcing the slot 33 against the wedge face of the pin 31 causing the gear to move from the full line to the dotted line position 40 of Fig. 4 and thereafter ride with the face 32 against the end 33 of the pin 31, with the pin free of the slot.

45 This movement is for the purpose of causing an immediate engagement between the pawl end 35 with the tooth 36, the lateral motion from the full line to the dotted line position of the pawl causing the pawl end 35 to contact immediately against the ratchet tooth.

50 It is to be understood that I employ a plurality of pawls as 17, 18 and that these have their engaging ends spaced on a pitch different from the pitch of the skew teeth of the ratchet, so that one or the other of said pawls is nearest to actual engagement with the ratchet tooth; and that then upon the first movement above described, when the gear 11 and pawls 17, 18 are laterally displaced from the full line to the dotted position the pawl which was originally nearest to the tooth is caused immediately to engage the tooth.

55 In this way, any lost motion between the pawls and ratchet teeth will be taken up and 60 a perfect accuracy of the paper movement

synchronous with the movement of the pump piston 2 is obtained.

It will thus be seen that the motion is transmitted from handle 8 and pump actuating rack 7 through the pinion 10, gear 11, and thence through the varying motion above described between the pawls 17, 18 and ratchet 19, to the main shaft 12, securing a movement of the main shaft 12 proportional to the movement of the rack 7 and therefore of the 75 pump piston 2.

This motion is transmitted through the friction plate 25 to the drum 20 so that within the limits of the friction the drum 20 moves in exact proportion to the pump piston 80 and therefore the paper strip or strips advance in exact synchronism with the pump piston 2.

If the paper sticks or if a new roll or rolls 85 be inserted they may be adjusted so that their graduations 38 are corresponding exactly with the position of the pump piston by rotating the drum 20 against the friction 25.

We claim:

1. Sales check mechanism for fluid dispensing apparatus comprising a member constrained to rotate in synchronism with said dispensing apparatus, a shaft on which said member is adapted to slide, a skew toothed ratchet on said shaft, means fixed to said ratchet for advancing record strips, and a plurality of pawls carried on said member and adapted to selectively engage the said ratchet teeth when the said member is rotated.

2. Sales check mechanism for fluid dispensing apparatus comprising a member constrained to rotate in synchronism with said dispensing apparatus, a shaft on which said member is adapted to slide, a skew toothed ratchet on said shaft, mechanism fixed to said ratchet for advancing record strips, and a plurality of pawls carried on said member and adapted to selectively engage the said ratchet teeth when the said member is rotated, means adapted to force said member laterally on the first increment of rotative movement thereby causing the pawls to move laterally and one of said pawls to engage the skew teeth on a minimum of rotative movement and a spring holding said member against said means.

3. Mechanism as set forth in claim 2 wherein the said mechanism includes a drum and in combination therewith with a plurality of paper strips adapted to be advanced by said drum on the rotation of said member.

4. Sales check mechanism for a fluid reciprocating pump comprising a member constrained to rotate in synchronism with said pump, a shaft on which said member is adapted to slide, a skew toothed ratchet on said shaft, mechanism fixed to said ratchet for advancing record strips, and a plurality of pawls carried on said member and adapted to se-

lectively engage the said ratchet teeth when the said member is rotated.

5. Sales check mechanism for a fluid reciprocating pump comprising a member constrained to rotate in synchronism with said pump, a shaft on which said member is adapted to slide, a skew toothed ratchet on said shaft, mechanism fixed to said ratchet for advancing record strips, and a plurality of 10 pawls carried on said member and adapted to selectively engage the said ratchet teeth

when the said member is rotated, means adapted to engage said member when the member is at one end of its operating range and to force said member laterally on the first 15 increment of rotative movement thereby causing the pawls to move laterally and one of said pawls to engage the skew teeth on a minimum of rotative movement and a spring holding said member against said means.
